Inventor:

E. Thayer

United States Patent Office.

ELI THAYER, OF NEW YORK, N. Y.

Letters Patent No. 61,119, dated January 8, 1867.

IMPROVEMENT IN BOOTS AND SHOES.

The Schedule referred to in these Letters Patent and making part of the same.

TO ALL WHOM IT MAY CONCERN:

Be it known that I, ELI THAYER, of the city, county, and State of New York, have invented a new and improved Method of Making the Soles of Boots and Shoes; and I do hereby declare that the following is a full and exact description thereof, reference being had to the accompanying drawings, and to the letters of reference marked thereon.

The nature of my invention consists in making the tap-soles of boots and shoes in several transverse sections. Its advantages over the method now in use, of attaching the outer sole in a single piece, are, first, greater flexibility; second, greater durability; third, it prevents "squeaking;" fourth, it allows a more free and natural action to the muscles and joints of the foot; fifth, it is much more economical, since the sole made in this way may be composed entirely of waste fragments of leather.

Figure 1 represents a side view of the sole of a boot or shoe, *a b c d*, &c., being the ends of the transverse sections.

Figure 2 represents the bottom of the sole, *a b c d*, &c., representing the transverse sections.

These sections may fit closely to each other, or they may be separated by a small space. They may be made of leather, rubber, metal, wood, or any other suitable material, and may be either solid or hollow. They may be attached to the upper sole by means of nails, pegs, rivets, screws, or thread, at the ends only, or throughout. They may consist of one layer or thickness, or of several, according to the service required of them. They may be attached to the principal sole before that is attached to the upper leather, or afterward. They may be attached in sections, or in one piece, and cut into sections afterward. In the latter case, provision would need to be made in the sewing or nailing, so that the subsequent dividing into sections might not injure the manufacture. But as this method is more expensive than the other, and in no way better, it is not likely to be used. The spaces between the sections may be either vacant or filled, wholly or in part, with some elastic substance.

Having now described its construction and use, what I claim as my invention, and desire to secure by Letters Patent, is—

The making the tap-soles of boots or shoes in several transverse sections of leather, substantially as set forth.

ELI THAYER.
